UNITED STATES PATENT OFFICE.

JOHN M. HANSEN, OF PITTSBURG, PENNSYLVANIA

TRUCK FOR RAILWAY-CARS.

No. 903,286

Specification of Letters Patent.

Patented Nov. 10, 1908.

Application filed January 24, 1908. Serial No. 412,487.

To all whom it may concern:

Be it known that I, JOHN M. HANSEN, a resident of Pittsburgh, in the county of Allegheny and State of Pennsylvania, have invented a new and useful Improvement in Trucks for Railway-Cars; and I do hereby declare the following to be a full, clear, and exact description thereof.

This invention relates to diamond side frames for railway trucks.

The object of the invention is to provide a side frame of the character described which is practically self-contained, in which the load is taken directly by the lower arch bar, and which is very strong and rigid.

The invention comprises the construction and arrangement of parts hereinafter described.

In the accompanying drawing Figure 1 is a plan view of the side frame and part of the spring plank; Fig. 2 is in part a vertical section and in part an elevation of the same; Fig. 3 is a vertical section on the line 3—3, Fig. 2; and Fig. 4 is a similar section 25 on the line 4—4, Fig. 2.

The side frame comprises the upper arch bar 1 which is shown as a section of channel bar placed with the flanges projecting upwardly, the lower arch bar 2 shown as a flat plate with its ends rigidly secured to the ends of the upper arch bar, such as by rivets 3, the pedestal tie bar 4, and the bolster guides or columns. The upper and lower arch bars are separated from each other intermediate their ends as usual, and at their central portions are connected by the bolster guides or columns. The latter are of special design, being shown as formed in a single integral casting of substantial 35 rectangular form in side elevation and comprising the vertical guide portions or columns 5, the top connecting member 6, and the bottom connecting member 7. The top connecting member 6 is strengthened by depending flanges 8 and the vertical columns are likewise strengthened by outwardly projecting flanges 9.

The casting described is connected to the upper arch bar by means of rivets 10 driven 50 through the arch bar and the top connecting member 6 of the casting, and also through flanges 11 at the upper ends of the columns 5. The vertical members or columns 5 at their lower ends are widened out and each is 55 provided with an opening 12, through which openings the lower arch bar 2 and the pedes-

tal tie bar 4 extend, said arch bar and tie bar resting upon the bottom 7 of the casting and being secured thereto by means of rivets 14. The bottom 7 of the casting is formed 60 with a depression 15 to receive the narrow tie bar 4, while the wider arch bar 2 rests upon said tie bar and lateral offset portions 16 of the casting. The holes 12 are of the shape shown in Figs. 3 and 4 so that the 65 arch bar 2 can be readily inserted and then brought to place by giving it a part turn. The bottom 7 of the casting is widened out laterally or sidewise as shown at 17, forming a wide base which is utilized as a spring 70 seat, without the necessity of adding a separate spring seat. The spring plank 18 may be either a channel or two angle bars, being shown as the latter, and being bolted to the casting through holes in the lateral bottom 75 portions 19 and vertical lateral webs 20.

The brake beam hangers 21 are shown as integral parts of the casting, being formed as arms projecting inwardly from the columns 5.

The side frame described may be used either with or without a rigid bolster, but preferably with a swinging bolster having its ends lying between the columns 5 and resting upon springs which are supported by 85 the spring plank and lower arch bar. The spring plank angle bars 18 rest directly upon the lower arch bar so that the load is in effect carried by the central portion of the lower arch bar and without placing any 90 rivets or bolts at this point under stress of any kind, as is the case with ordinary pedestal trucks in which the lower arch bar lies below the lower ends of the columns. Such old construction is objectionable, as the horizontal rivets of the spring plank are put 95 under shearing stresses, while the vertical rivets fastening the arch bar to the columns are put in tension. This is a point of weakness of ordinary diamond frame trucks, as, 100 on account of the restricted space at the lower ends of the columns, the number of rivets which can be employed is limited. By the construction shown in the drawings this is overcome, as none of the bolts or 105 rivets at the lower ends of the columns are put under any stresses whatever, but the load resting on the spring plank is transmitted directly and by actual contact to the lower arch bar, and then transmitted 110 through the lower arch bar to the ends of the top arch bar and through the vertical

columns to the central portion of the top arch bar. The central portion of the lower arch bar is practically suspended through the columns from the central portion of the 5 top arch bar. The columns are very securely fastened to the top arch bar, since there is no restriction as to space or as to the number of rivets which can be placed at this point.

10 The side frame described forms a very rigid structure, practically as rigid as a single integral frame of the same conformation. The number of parts is reduced to a minimum, and the rectangular column casting with top and bottom connecting members forms a brace and prevents vibration. I do not, however, limit the invention to the integral casting, as all of the advantage of supporting the load directly on the lower 20 arch bar could be secured if said column casting were made in several pieces instead of integral, as shown.

What I claim is:

1. A diamond side frame for trucks comprising upper and lower arch bars rigidly secured together at their ends, and separated at intermediate points, and a bolster guide member consisting of a single integral casting and comprising two guide columns with 25 top and bottom portions, the top portion being secured to the upper arch bar and the vertical portions or columns being provided at their lower ends with openings through 30 which the lower arch bar extends.
2. A diamond side frame for trucks comprising upper and lower arch bars rigidly secured together at their ends and separated at their intermediate points, a casting between the middle portions of said arch bars 35 and comprising vertical columns and top and bottom connecting members, the top connecting member being secured to the upper arch bar, and the lower arch bar resting upon and being secured to the lower connecting 40 member, and a spring plank resting on said lower arch bar and lower connecting member.
3. A diamond side frame for trucks comprising upper and lower arch bars rigidly 45

secured together at their ends and separated 50 at intermediate points, and a substantial rectangular casting between said arch bars, said casting comprising vertical columns provided with openings near their ends through which the bottom arch bar and the pedestal 55 tie bar project, a top connecting portion secured to the upper arch bar, and a bottom connecting plate upon which the bottom arch bar and tie bar rest and to which they are secured.

4. A diamond side frame for trucks comprising upper and lower arch bars rigidly secured together at their ends and separated at intermediate points, and a bolster guide member comprising vertical columns and 65 top and integral bottom connecting members secured, respectively, to the upper and lower arch bars, the bottom connecting member being extended laterally to form a spring seat.

5. A column guide member for diamond frame trucks comprising two column guides and top and bottom connecting portions, said columns at their lower portions being provided with openings for the lower arch bar.

6. A column guide member for diamond frame trucks comprising vertical columns and top and bottom connecting portions, said columns at their lower ends being provided with openings for the lower arch bar, 80 and the bottom connecting portion being widened laterally to form a spring seat.

7. A column guide member for diamond frame trucks, comprising two vertical columns and top and bottom connecting members, the vertical columns being provided at their bottoms with openings for receiving the lower arch bar and the pedestal tie bar, and the bottom connecting member being grooved to seat the pedestal tie bar and receive the wider arch bar on top of the same.

In testimony whereof, I the said JOHN M. HANSEN have hereunto set my hand.

JOHN M. HANSEN.
